UNITED STATES PATENT OFFICE.

SOLOMON ROGERS, OF CHATTANOOGA, TENNESSEE, ASSIGNOR OF ONE-FOURTH TO
WILLIAM BUFORD, OF CHATTANOOGA, TENNESSEE.

AUTOMATIC TRAIN-STOP.

1,123,013.

Specification of Letters Patent.

Patented Dec. 29, 1914.

Application filed February 4, 1914. Serial No. 816,543.

To all whom it may concern:

Be it known that I, SOLOMON ROGERS, a citizen of the United States, residing at Chattanooga, in the county of Hamilton 5 and State of Tennessee, have invented new and useful Improvements in Automatic Train-Stops, of which the following is a specification.

This invention relates to improvements in 10 automatic train stops and has particular application to a signal controlled train stopping apparatus.

In carrying out the present invention, it is 15 my purpose to provide an apparatus of the class described whereby the air brake system of a car or train will be automatically brought into service in the event of such car or train entering an occupied block against a danger signal and which will embody few 20 parts and these so correlated and arranged as to reduce the possibility of derangement to a minimum.

It is also my purpose to provide an apparatus of the type set forth which will embrace the desired features of simplicity, efficiency and durability and one which may be installed and maintained at a minimum expense.

With the above and other objects in view, 30 the invention consists in the construction, combination and arrangement of parts hereinafter set forth in and falling within the scope of the claims.

In the accompanying drawing; Figure 1 35 is a transverse sectional view through a trackway and locomotive thereon showing the relative positions of the car carried mechanism and the signal blade. Fig. 2 is a diagrammatic view of the car carried mechanism, the same being shown on an enlarged scale and partly in section.

Referring now to the drawing in detail, 40 1 designates a locomotive adapted to travel over the trackway 2, whilst 3 indicates the standard or post of a semaphore, and 4 the signal blade pivoted to the upper end of the standard and capable of movement to clear and danger position.

5 indicates the train line air pipe or brake 45 pipe of the air brake system of the train or car, such pipe extending into the cab of the locomotive and is provided with the usual engineer's valve 6. Tapped onto the portion of the train line air pipe within the

locomotive is a branch pipe 7 opening into the atmosphere as at 8 and formed with a vertical portion. Connected in the vertical portion of the pipe 7 is a cut off valve 9 having the vertical stem thereof provided with a horizontal handle 10, while uprising from the horizontal portion of the pipe 7 in proximity to the stem of the valve 9 is a pivot pin 11. A vertical shaft 12 projects through the roof of the cab of the locomotive and has the lower end thereof formed with a socket 13 receiving the pin 11 on the respective portion of the pipe 7, while connected to the upper end of the shaft 12 and arranged at right angles thereto is a lever 14 normally held at right angles to the path of movement of the car by a spring 15.

Projecting outwardly from the shaft 12 adjacent to the lower end thereof is an arm 16 provided with a depending finger 17 terminating at one side of the handle 10 of the valve 9 and adapted when the shaft 12 is rotated to swing the handle 10 so as to open the valve and establish communication between the train line air pipe and the atmosphere.

In practice, when a signal blade is thrown to danger position, the outer end of such blade is disposed in the path of movement of the outer end of the arm 14 of an oncoming car and in the event of the car passing 85 the danger signal the outer end of the arm 14 contacts with the signal blade and the shaft 12 is rotated against the action of the spring 15. In the rotation of the shaft 12, the finger 17 on the arm 16 moves the handle 90 10 of the valve 9 thereby opening the latter and bleeding the train line air pipe. Succeeding the release of the arm 14 by the signal blade, the spring 15 restores such arm to normal position while the valve 9 remains 95 open and to close the latter the handle 10 is grasped by the engineer and swung to closed position.

I claim:

1. The combination with the train line air pipe, of a branch pipe connected thereto, a valve in said branch pipe, a handle for said valve, a pivot pin carried by said pipe adjacent to said valve, a shaft having one end thereof socketed to receive said pin, a lever carried by the other end of said shaft, an arm extending outwardly from said shaft and adapted when the latter is rotated to

engage said handle and open the valve, and means for operating said lever to rotate said shaft.

2. The combination with the train line air pipe, of a branch pipe connected thereto, a valve in said branch pipe, a handle for said valve, a pivot pin carried by said pipe adjacent to said valve, a shaft having one end thereof socketed to receive said pin, a lever 10 carried by the other end of said shaft, an arm extending outwardly from said handle and adapted when the latter is rotated to engage said handle and open the valve, means for operating said lever to rotate said shaft, 15 and means holding said lever in normal position and adapted to restore the same to such position.

3. The combination with the train line air pipe, of a branch pipe connected thereto and

having a horizontal portion, a valve connected in said horizontal portion, a handle on said valve, a pivot pin carried by the horizontal portion of said branch pipe, a vertical shaft having the lower end thereof socketed to receive said pin, a lever connected to the upper end of said vertical shaft, an arm projecting outwardly from said shaft, a finger depending from said arm, means for actuating said lever to rotate said shaft whereby said finger will engage said valve handle to open the valve, and means for restoring said lever to normal position.

In testimony whereof I affix my signature in presence of two witnesses.

SOLOMON ROGERS.
